POLISH ROD HANGER

Calvin W. Shelton, Borger, Tex., assignor to J. M. Huber Corporation, Locust, N. J., a corporation of New Jersey

Application October 17, 1950, Serial No. 190,525

10 Claims. (Cl. 255—14)

1

This invention relates to polish rod hangers and more particularly to an improved form of polish rod hanger and rotator.

In the operation of an oil well, the pump at the bottom of the well is operated by reciprocating a string of pump rods by means of the rocking motion of a beam powered by means of a suitable pump unit. It is usual to connect the top pump rod, conventionally called a polish rod, with the beam by means of a hanger which is suspended by cables from the end of the beam. In the more modern forms, the hanger usually includes slip means which normally grip the polish rod but release the rod when there is resistance to the downward motion of the rod so that the hanger can move downward relatively to the rod. Also, means are generally provided for intermittently rotating the polish rod during certain periods of its reciprocation so as to maintain the joints of the pump rods tight and also, so as to operate scraping means fastened on the pump rods. It is therefore common to construct the polish rod hanger so as to permit the polish rod to rotate relatively to the hanger. Representative equipment of this character is shown by Johnston in Patent 2,280,408 and by McConahey et al. in Patent 2,444,842.

The pumping equipment, including the polish rod hanger and the rotating means, are positioned above the ground and are usually open to the weather. The rotating means usually comprises a ratchet turntable or wheel operated by a ratchet pawl which is in turn operated by means of a cable also attached to the rocking beam. There is a tendency for the ratchet turntable to be clogged by rust, dirt, ice and snow so as to prevent proper engagement of the actuating pawl therewith and thus render the rotating mechanism inoperative. Also, there is a tendency for the slip means in the hangers to be rendered inoperative by dirt, rust, ice, snow and/or thickened or congealed lubricant.

Usually the ratchet turntable is firmly secured to the polish rod so that there can be no motion of the rod relatively to the turntable. The actuating pawl for the ratchet turntable is usually secured to the hanger. Such structure necessarily limits the permissible vertical movement of the hanger relative to the polish rod, frequently to such an extent that the desired purpose is not completely accomplished, as when the motion of the rod is stopped near the top of its stroke. Also, in such structure, the rotating mechanism continues to operate even when the downward motion of the polish rod is obstructed and the rod

2

is held against rotation, thereby placing undesired torsional stresses on the rod. Furthermore, hangers, containing slip means, will slide down the polish rod when the downward motion of the rod is prevented, but will again grip the rod immediately at the start of the upward motion of the hanger and hence at a position below that normally desired, whereby continued operation of the hanger will permit downward motion of the polish rod only to the position where the obstruction originally occurred, even though such obstruction has been removed, and will raise the polish rod to an undesirably elevated position.

It is an object of my invention to provide a new and improved polish rod hanger and rotator. Another object is to provide a polish rod hanger and rotator wherein the ratchet turntable and pawl are enclosed in a casing which protects them from being rendered inoperative by rust, dirt, ice and snow, and which holds a body of lubricant to maintain the rotating mechanism lubricated. A further object is to provide a polish rod hanger and rotator which is slidably mounted on the polish rod so that it can move downward relatively to the rod to any necessary extent, and will not alter the normal reciprocating position of the polish rod. Still another object is to provide a polish rod hanger and rotator which may slide downward relatively to the rod and which is so constructed that the rotating mechanism is immediately rendered inoperative to rotate the rod, when the hanger is so moved. A still further object is to provide a polish rod hanger and rotator of the above character which is simple and economical in design and in which the parts are so constructed and arranged that they can be readily removed from the polish rod for repair, replacement and the like. Other objects are to provide a new article of manufacture and to advance the art. Still other objects will appear hereinafter.

The above and other objects may be accomplished in accordance with my invention which comprises a polish rod hanger and rotator that is adapted to support a polish rod and to impart a reciprocating motion and an intermittent rotating motion to the polish rod, which polish rod hanger and rotator comprises a vertically reciprocating hanger bar slidably mounted on the polish rod, a substantially annular casing slidably mounted on the polish rod above the hanger bar and supported by the hanger bar, a ratchet turntable rotatably mounted in the casing, a ratchet actuating pawl mounted in the casing, a rotatable plate at the top of the casing, means

firmly securing the rotatable plate to the ratchet turntable for rotation therewith, and a clamp firmly secured to the polish rod above the rotatable plate and normally supported by and only frictionally engaging the upper surface of the rotatable plate. Preferably, the annular casing is closed so as to hold a body of lubricant and to prevent the entrance of water, dirt, ice and snow and which casing completely encloses the ratchet turntable and actuating pawl so as to protect them from dirt, water, ice and snow and maintains the ratchet turntable and the pawl continuously lubricated.

Preferably, the casing comprises an inner cylindrical side wall having an internal diameter slightly larger than the diameter of the polish rod so that it may slide freely over the polish rod, an outer substantially cylindrical side wall spaced laterally from the inner side wall so as to provide an annular space for the ratchet turntable, an annular bottom wall at the lower end of the side walls completely closing the lower end of the annular space between the side walls and rotatably supporting the ratchet turntable so as to provide an annular receptacle which will hold a lubricant for lubricating the ratchet turntable, and an annular cover plate rotatably mounted over the upper ends of the side walls and covering the upper end of the space between the side walls so as to prevent dirt, water, snow and ice from entering the casing, the cover plate being secured to the ratchet turntable by means positioned between the side walls of the casing so that the cover plate will rotate with the turntable. Preferably, the lower surface of the cover plate is recessed to receive the upper ends of the side walls so as to more certainly prevent the entrance of dirt, water, ice and snow into the casing. Also preferably, the annular casing is not secured to the hanger bar, but normally merely rests upon and only frictionally engages the hanger bar so that it can be removed from the polish rod independently of the hanger bar for cleaning, repairing or replacement.

My invention will be more readily understood from the detailed description hereinafter given, when taken with the accompanying drawings which illustrate preferred embodiments of the structure of my invention and in which

Figure 1 is a somewhat diagrammatic illustration, with parts in section, illustrating a conventional assembly of oil well pump equipment with which my invention is adapted to be employed;

Figure 2 is an enlarged view showing the general relation of the hanger bar, casing, and clamp of my invention;

Figure 3 is a detailed view, partly in section, illustrating one form of polish rod hanger and rotator of my invention;

Figure 4 is a vertical sectional view taken on line 4—4 of Figure 3;

Figure 5 is a horizontal cross sectional view taken on line 5—5 of Figure 3;

Figure 6 is a view similar to Figure 3, showing a modified form of construction of the cover plate.

Referring first to Figures 1 and 2, the numeral 10 indicates a Samson post supporting a pump jack beam 12. The beam 12 is operated by a pitman rod 14 which is connected with the driving disc 16 of the pump unit 18. A cable 20 is supported on the outer end of the beam 12 and is connected with and carries the polish rod hanger bar 22. The hanger bar, through mechanism to be described, carries and reciprocates polish rod

24 which extends down through a string of pipe 26 supported on a header 28. The polish rod and the pump rods attached to the lower end thereof and the string of pipe extend down through the well casing 30 to the bottom of the well and to the pump therein. The structure, as so far specifically described, is conventional and its purpose and mode of operation are well known to those skilled in the art.

In the structure of my invention, the hanger bar 22 is slidably mounted on the polish rod 24. In other words, the bore in the hanger bar, through which the polish rod passes, is slightly larger than the diameter of the polish rod so that the hanger bar fits loosely over the polish rod and the hanger bar can freely slide downward relative to the polish rod whenever for any reason the polish rod is prevented from moving downward.

Referring more particularly to Figures 3 to 5, a substantially annular casing, indicated generally by the numeral 32, is also slidably mounted on the polish rod above the hanger bar. Such casing 32 comprises an inner cylindrical side wall 34, an outer substantially cylindrical side wall 36, an annular bottom wall 38, and an annular cover plate 40. The inner cylindrical wall 34 has an internal diameter slightly larger than the diameter of the polish rod so that such wall fits sufficiently loosely on the polish rod and will freely slide over the polish rod. The outer side wall 36 is provided with an outwardly projecting portion 42 for supporting an actuating pawl 48. Otherwise, the wall 36 is cylindrical and coextensive vertically with the inner wall 34, and is spaced laterally from the inner wall 34 so as to provide an annular space to receive the ratchet turntable, the bearings therefor and a body of lubricant. The bottom wall 38 extends from the bottom of the side wall 34 to the bottom of the side wall 36 and completely closes the lower end of the space between the side walls. Preferably, the walls 34, 36, and 38 are made integral with each other.

Preferably, the casing 32 is not fastened to the hanger bar 22, but is normally supported by and only frictionally engages the hanger bar. If desired, the lower surface of the bottom wall 38 may be roughened as shown so as to increase the friction between it and the upper surface of the hanger bar and to further hinder any rotation of the casing. However, it will be understood that the casing 32 may be detachably secured to the hanger bar by any suitable means, such as a flange or lugs at the lower portion of the casing and bolts and nuts or the like. Also, if desired, the casing 32 may be permanently secured to the hanger bar or made integral therewith, but such construction is generally undesired as it will prevent removal of the casing and the rotating mechanism from the polish rod independently of the hanger bar.

A ratchet turntable 44 is rotably mounted within the casing 32 on roller bearings 46 of conventional design. Obviously, ball bearings, or bearings of other conventional types, may be substituted for the roller bearings. The ratchet turntable is operated by an actuating pawl 48 pivotally mounted on the eccentric 50 on the end of a shaft 54. As shown, the shaft 54 is rotatably mounted in ball bearings 56 in the outwardly projecting portion 42 of the outer wall 36. The outer end of the shaft 54 carries a lever 58 which is connected to the beam 12 by a cable 60 in the usual manner. A holding dog 75 62 is pivoted on pin 64 mounted in the side wall

5

36. Such holding dog 62 engages the ratchet teeth of the ratchet turntable in the usual manner to prevent reverse rotation of the ratchet turntable. The outer wall 36 is provided with one or more oil holes 66 for the introduction of oil or other lubricant through an oil cup or the like. Such oil hole is generally positioned above the ratchet turntable so that the body of oil in the casing will cover the ratchet turntable and provide a layer of protective lubricant over the teeth of the ratchet.

As shown, a cylindrical wall or ring 68 is positioned between the side walls 34 and 36 and preferably inwardly of the teeth of the ratchet turntable 44. Such cylindrical wall 68 rests upon and is supported by the ratchet turntable. The lower end of the wall 68 is firmly secured to the ratchet turntable by set pins 70 or the like. The upper end of the cylindrical wall 68 abuts against and supports the cover plate 40. Such cylindrical wall 68 is firmly secured to the cover plate by screws 72 as shown in Figure 3. Thus the cover plate 40 is supported by and firmly secured to the ratchet turntable 44 for rotation therewith.

The cover plate 40 is annular and extends over the ends of the side walls 34 and 36 and over the annular space between them so as to prevent dirt, rain, ice and snow from entering into the casing. The inner bore of the cover plate is slightly larger in diameter than the diameter of the polish rod so that it fits loosely on the polish rod and will freely slide thereover. The outer edge of the cover plate may extend beyond the side wall 36 by any desired amount.

Adjacent its inner edge, the under side of the cover plate 40 is provided with an annular recess 74 to receive the tapered upper end of the inner side wall 34. The under surface of the cover plate 40 is also provided with an annular recess 76 near its outer edge to receive the upper end of the outer wall 36. Preferably, a snap ring 78 is provided in the outer surface of the upper end of the outer wall 36 between such wall and the vertical surface of the recess 76 in the cover plate so as to more certainly prevent the entrance of moisture and the like into the casing 32.

A clamp 80 is firmly secured to the polish rod 24 by nuts and bolts 82. Such clamp 80 is not secured to the hanger bar, the casing or the cover plate 40, but its lower surface normally rests upon and frictionally engages the upper surface of the cover plate 40. The clamp is in the form of a split collar with outwardly extending vertical flanges on each half to accommodate the fastening means for securing them together and to the polish rod, and is of substantial height to provide a large surface contact with the polish rod. The mutually contacting surfaces of the clamp and of the cover plate may be roughened to increase the friction between them, or smoothed to decrease the friction, as desired. Also, the form of the clamp may be widely varied, particularly to vary the area of the surface which contacts the cover plate so as to vary the friction between them, such as by providing an outwardly extending flange at the lower end of the clamp.

Figure 6 illustrates a slightly modified form of the structure shown in Figures 3 to 5. In this modified form, the cylindrical wall 68 is secured to the cover plate 40 by welding, as shown at 86. Also, a single annular recess 88 is provided in the lower surface of the cover plate 40 to receive the upper ends of both of the end walls 34 and 36.

6

In normal operation, the polish rod 24 will be carried by the clamp 80 which is supported by the hanger bar 22 through the cover plate 40, the cylindrical wall 68, the turntable 44, and the casing 32. Upon operation of the rocker beam 12, the polish rod will be reciprocated by reciprocation of the hanger bar 22 in the manner well known to the art. At the same time, the actuating pawl 48 will be operated in the conventional manner to intermittently rotate the ratchet turntable 44 and the cover plate 40, and the cover plate will transmit such motion to the clamp 80 and the polish rod through friction between the upper surface of the cover plate and the bottom surface of the clamp. However, if the downward motion of the polish rod 24 is prevented by an obstruction in the well or the pump, or for other reason, the hanger bar and the casing 32 will continue their downward movement, sliding over the polish rod 24, and the cover plate 40 will be immediately disengaged from the clamp 80, whereby continued operation of the ratchet pawl and ratchet turntable will be inoperative to rotate the polish rod. When the hanger bar is thereafter moved upward, it will carry the casing 32 with it, but the cover plate 40 will not engage the clamp 80 until it has been raised to the position at which the downward motion of the polish rod and the clamp had stopped. Further upward motion of the hanger will usually lift the polish rod from the obstruction before the friction, between the cover plate and the clamp, becomes sufficient to cause the rotating mechanism to exert any appreciable rotating stress on the polish rod. If, due to any difficulty in the oil well or pump, the rotation of the polish rod is prevented or seriously resisted while it is supported by the hanger and rotator, the continued operation of the ratchet turntable will fail to impose any damaging torsional stress on the polish rod, because of the frictional engagement of the cover plate 40 with the clamp 80 which will permit rotation of the plate 40 independently of the clamp 80 when the force, required to rotate the polish rod, becomes excessive.

It will be understood that the structure, shown in the drawings and described in detail, is given solely for illustrative purposes, and that many variations and modifications may be made therein without departing from the spirit or scope of my invention. For example, the cover plate 40 and the turntable 44 may be secured together by other suitable means, such as bars, rods, bolts and nuts, a lattice-like framework, and the like. Also, the ratchet turntable may be turned over with the ratchet teeth and actuating pawl beneath and the turntable placed against the bottom of the cover plate and secured thereto by welding, screws, bolts and nuts and the like. Some other modifications have been indicated in the detailed description. Still other modifications will become apparent to those skilled in the art.

From all of the above, it will be apparent that I have provided a simple and sturdy polish rod hanger and rotator which has many advantages over the structures of the prior art. The ratchet turntable and pawl are protected from rust, dirt, ice and snow so that they will remain operative over long periods of time irrespective of weather conditions and are kept well lubricated so that their useful life is greatly extended. At the same time, the rotating mechanism is immediately rendered inoperative when the desired motion of

the polish rod is hindered in any way. Also, the hanger and rotator are free to move downward on the polish rod to any extent required by the position at which the downward motion of the polish rod is stopped and will not exert any objectionable stresses on the polish rod. Further, the hanger and rotator automatically restore and maintain the normal operation of the polish rod when any obstruction is removed. Furthermore, the casing and rotating mechanism are readily installed and removed for repairs, replacement or cleaning. Thus, it will be apparent that my invention constitutes a valuable contribution and advance in the art.

I claim:

1. A polish rod hanger and rotator, adapted to support a polish rod and to impart a reciprocating motion and an intermittent rotating motion to the polish rod, which comprises a vertically reciprocating hanger bar slidably mounted on the polish rod; a closed substantially annular casing slidably mounted on the polish rod above the hanger bar and supported by the hanger bar, which casing comprises an inner cylindrical side wall having an internal diameter slightly larger than the diameter of the polish rod, an outer substantially cylindrical side wall spaced laterally from the inner side wall, an annular bottom wall at the lower end of the side walls completely closing the lower end of the annular space between the side walls, an annular cover plate rotatably mounted over the side walls and covering the upper end of the space between the side walls; a ratchet turntable rotatably mounted within the casing between the side walls; means between the side walls firmly securing the cover plate to the ratchet turntable for rotation therewith; a ratchet actuating pawl mounted in the casing; pawl actuating means outside of the casing operatively connected to the ratchet actuating pawl; and a clamp firmly secured to the polish rod above the cover plate and normally supported by and only frictionally engaging the upper surface of the cover plate.

2. A polish rod hanger and rotator, adapted to support a polish rod and to impart a reciprocating motion and an intermittent rotating motion to the polish rod, which comprises a vertically reciprocating hanger bar slidably mounted on the polish rod; a closed substantially annular casing slidably mounted on the polish rod above the hanger bar and supported by the hanger bar, which casing comprises an inner cylindrical side wall having an internal diameter slightly larger than the diameter of the polish rod, an outer substantially cylindrical side wall spaced laterally from the inner side wall, an annular bottom wall extending from the lower end of one side wall to the lower end of the other side wall and completely closing the lower end of the annular space between the side walls, an annular cover plate rotatably mounted over the upper ends of the side walls and extending over the upper end of the annular space between the side walls, the lower surface of the cover plate being recessed to receive the upper ends of the side walls; a ratchet turntable rotatably mounted within the casing between the side walls; means between the side walls firmly securing the cover plate to the ratchet turntable for rotation therewith; a ratchet actuating pawl mounted in the casing; pawl actuating means outside of the casing operatively connected to the ratchet actuating pawl; and a clamp firmly secured to the polish rod above the cover plate and normally supported

by and only frictionally engaging the upper surface of the cover plate.

3. A polish rod hanger and rotator, adapted to support a polish rod and to impart a reciprocating motion and an intermittent rotating motion to the polish rod, which comprises a vertically reciprocating hanger bar slidably mounted on the polish rod; a closed substantially annular casing slidably mounted on the polish rod above the hanger bar and supported by the hanger bar, which casing comprises an inner cylindrical side wall having an internal diameter slightly larger than the diameter of the polish rod, an outer substantially cylindrical side wall spaced laterally from the inner side wall, an annular bottom wall extending from the lower end of one side wall to the lower end of the other side wall and completely closing the lower end of the annular space between the side walls, an annular cover plate rotatably mounted over the upper ends of the side walls and extending over the upper end of the annular space between the side walls; a ratchet turntable rotatably mounted within the casing between the side walls; a cylindrical supporting wall extending from the ratchet turntable to the cover plate between the side walls of the casing and firmly secured to both the turntable and the cover plate; a ratchet actuating pawl mounted in the casing; pawl actuating means outside of the casing operatively connected to the ratchet actuating pawl; and a clamp firmly secured to the polish rod above the cover plate and normally supported by and only frictionally engaging the upper surface of the cover plate.

4. A polish rod hanger and rotator, adapted to support a polish rod and to impart a reciprocating motion and an intermittent rotating motion to the polish rod, which comprises a vertically reciprocating hanger bar slidably mounted on the polish rod; a closed substantially annular casing slidably mounted on the polish rod above the hanger bar and supported by the hanger bar, which casing comprises an inner cylindrical side wall having an internal diameter slightly larger than the diameter of the polish rod, an outer substantially cylindrical side wall spaced laterally from the inner side wall, an annular bottom wall extending from the lower end of one side wall to the lower end of the other side wall and completely closing the lower end of the annular space between the side walls, an annular cover plate rotatably mounted over the upper ends of the side walls and extending over the upper end of the annular space between the side walls, the lower surface of the cover plate being recessed to receive the upper ends of the side walls; a ratchet turntable rotatably mounted within the casing between the side walls; a cylindrical supporting wall extending from the ratchet turntable to the cover plate between the side walls of the casing and firmly secured to both the turntable and the cover plate; a ratchet actuating pawl mounted in the casing; pawl actuating means outside of the casing operatively connected to the ratchet actuating pawl; and a clamp firmly secured to the polish rod above the cover plate and normally supported by and only frictionally engaging the upper surface of the cover plate.

5. A polish rod hanger and rotator, adapted to support a polish rod and to impart a reciprocating motion and an intermittent rotating motion to the polish rod, which comprises a vertically reciprocating hanger bar slidably mounted on

the polish rod; a closed substantially annular casing slidably mounted on the polish rod above the hanger bar and normally supported by and only frictionally engaging the hanger bar, which casing comprises an inner cylindrical side wall having an internal diameter slightly larger than the diameter of the polish rod, an outer substantially cylindrical side wall spaced laterally from the inner side wall, an annular bottom wall at the lower end of the side walls completely closing the lower end of the annular space between the side walls, an annular cover plate rotatably mounted over the side walls and covering the upper end of the space between the side walls; a ratchet turntable rotatably mounted within the casing between the side walls; means between the side walls firmly securing the cover plate to the ratchet turntable for rotation therewith; a ratchet actuating pawl mounted in the casing; pawl actuating means outside of the casing operatively connected to the ratchet actuating pawl; and a clamp firmly secured to the polish rod above the cover plate and normally supported by and only frictionally engaging the upper surface of the cover plate.

6. A polish rod hanger and rotator, adapted to support a polish rod and to impart a reciprocating motion and an intermittent rotating motion to the polish rod, which comprises a vertically reciprocating hanger bar slidably mounted on the polish rod; a closed substantially annular casing slidably mounted on the polish rod above the hanger bar and normally supported by and only frictionally engaging the hanger bar, which casing comprises an inner cylindrical side wall having an internal diameter slightly larger than the diameter of the polish rod, an outer substantially cylindrical sidewall spaced laterally from the inner side wall, an annular bottom wall extending from the lower end of one side wall to the lower end of the other side wall and completely closing the lower end of the annular space between the side walls, an annular cover plate rotatably mounted over the upper ends of the side walls and extending over the upper end of the annular space between the side walls, the lower surface of the cover plate being recessed to receive the upper ends of the side walls; a ratchet turntable rotatably mounted within the casing between the side walls; means between the side walls firmly securing the cover plate to the ratchet turntable for rotation therewith; a ratchet actuating pawl mounted in the casing; pawl actuating means outside of the casing operatively connected to the ratchet actuating pawl; and a clamp firmly secured to the polish rod above the cover plate and normally supported by and only frictionally engaging the upper surface of the cover plate.

7. A polish rod hanger and rotator, adapted to support a polish rod and to impart a reciprocating motion and an intermittent rotating motion to the polish rod, which comprises a vertically reciprocating hanger bar slidably mounted on the polish rod; a closed substantially annular casing slidably mounted on the polish rod above the hanger bar and normally supported by and only frictionally engaging the hanger bar, which casing comprises an inner cylindrical side wall having an internal diameter slightly larger than the diameter of the polish rod, an outer substantially cylindrical side wall spaced laterally from the inner side wall, an annular bottom wall extending from the lower end of one side wall to the lower end of the other side wall

and completely closing the lower end of the annular space between the side walls, an annular cover plate rotatably mounted over the upper ends of the side walls and extending over the upper end of the annular space between the side walls, the lower surface of the cover plate being recessed to receive the upper ends of the side walls; a ratchet turntable rotatably mounted within the casing between the side walls; a cylindrical supporting wall extending from the ratchet turntable to the cover plate between the side walls of the casing and firmly secured to both the turntable and the cover plate; a ratchet actuating pawl mounted in the casing; pawl actuating means outside of the casing operatively connected to the ratchet actuating pawl; and a clamp firmly secured to the polish rod above the cover plate and normally supported by and only frictionally engaging the upper surface of the cover plate.

8. A polish rod rotator which comprises a closed substantially annular casing adapted to be slidably mounted on a polish rod above a hanger bar, which casing comprises an inner cylindrical side wall having an internal diameter slightly larger than the diameter of the polish rod, an outer substantially cylindrical side wall spaced laterally from the inner side wall, an annular bottom wall at the lower end of the side walls completely closing the lower end of the annular space between the side walls, an annular cover plate rotatably mounted over the upper ends of the side walls and covering the upper end of the space between the side walls; a ratchet turntable rotatably mounted within the casing between the side walls; means between the side walls firmly securing the cover plate to the ratchet turntable for rotation therewith; and a ratchet actuating pawl mounted in the casing; and pawl actuating means outside of the casing operatively connected to the ratchet actuating pawl.

9. A polish rod rotator which comprises a closed substantially annular casing adapted to be slidably mounted on a polish rod above a hanger bar, which casing comprises an inner cylindrical side wall having an internal diameter slightly larger than the diameter of the polish rod, an outer substantially cylindrical side wall spaced laterally from the inner side wall, an annular bottom wall at the lower ends of the side walls and completely closing the lower end of the annular space between the side walls, an annular cover plate rotatably mounted over the upper ends of the side walls and extending over the upper end of the annular space between the side walls, the lower surface of the cover plate being recessed to receive the upper ends of the side walls; a ratchet turntable rotatably mounted within the casing between the side walls; means between the side walls firmly securing the cover plate to the ratchet turntable for rotation therewith; and a ratchet actuating pawl mounted in the casing; and pawl actuating means outside of the casing operatively connected to the ratchet actuating pawl.

10. A polish rod rotator which comprises a closed substantially annular casing adapted to be slidably mounted on a polish rod above a hanger bar, which casing comprises an inner cylindrical side wall having an internal diameter slightly larger than the diameter of the polish rod, an outer substantially cylindrical side wall spaced laterally from the inner side wall, an annular bottom wall at the lower ends of the side

walls and completely closing the lower end of the annular space between the side walls, an annular cover plate rotatably mounted over the upper ends of the side walls and extending over the upper end of the annular space between the side walls, the lower surface of the cover plate being recessed to receive the upper ends of the side walls; a ratchet turntable rotably mounted within the casing between the side walls; a cylindrical supporting wall extending from the ratchet turntable to the cover plate between the side walls of the casing and firmly secured to both the turntable and the cover plate; and a ratchet actuating pawl mounted in the casing; and pawl actuating means outside of the casing

15

operatively connected to the ratchet actuating pawl.
